UNITED STATES PATENT OFFICE.

GRANT W. ROLLINS, OF TOLEDO, OHIO, ASSIGNOR TO THE WILLYS-OVERLAND COMPANY, OF TOLEDO, OHIO, A CORPORATION OF OHIO.

METAL-WORKING MACHINE.

Application filed June 21, 1919. Serial No. 305,841.

To all whom it may concern:

Be it known that I, GRANT W. ROLLINS, a citizen of the United States, residing at Toledo, county of Lucas, and State of Ohio, have invented certain new and useful Improvements in Metal-Working Machines, of which I declare the following to be a full, clear, and exact description.

This invention relates to a metal working machine, more particularly a machine which is adapted to be employed for the purpose of forcing a pin within an opening or openings formed in one or more elements constructed in such a manner as to produce a tight fit between the parts.

One object of this invention is to provide a device of this character which is of simple construction and efficient in operation.

A further object of the invention is to provide a device of this character which is automatic in its operation and which may be employed for the purpose of readily and quickly forcing a pin within an opening formed in a metal element.

A further object of the invention is to provide means for properly centering the opening formed in the metal element with the pin which is adapted to be driven therein in such a manner as to prevent distortion 30 of the parts and facilitate the ease with which the operation is performed.

A further object of the invention is to provide suitable means for firmly securing in proper position relative to each other, 35 a pair of elements which are provided with registering openings, while a pin is being driven within the registering openings of the elements.

Further objects of this invention relate 40 to economies of manufacture and details of construction, as will hereinafter appear from the detailed description to follow.

The objects of the invention are accomplished in one instance by the devices and 45 means described in the following specification, but it is evident that the same may be varied widely without departing from the scope of the invention as pointed out in the appended claims.

50 A structure constituting one embodiment of the invention, which may be the preferred, is illustrated in the accompanying drawings forming a part hereof in which:

Figure I is a side elevational view of the

machine, the plunger being shown in raised 55 position.

Figure II is a side elevational view of a portion of the operating mechanism of the machine, the plunger being shown in depressed position.

Figure III is a horizontal sectional view, taken along the line III—III of Figure I, and illustrating the relative position of the block or casing, and the means for actuating 60 the plunger.

Figure IV is a horizontal sectional view, taken along the line IV—IV of Figure I, and illustrating in detail the valve operating mechanism for actuating the plunger.

Figure V is a vertical sectional view taken 70 along the line V—V of Figure III and illustrating the position of the operating mechanism and the elements adapted to be operated upon when the plunger is in depressed position.

Referring to the drawings, similar reference characters designate corresponding parts throughout the several views, and the sectional views are taken looking in the direction of the small arrows at the ends of 75 the section lines.

In the embodiment of the invention illustrated herewith, 1 indicates a supporting standard which is preferably provided with an enlarged base portion 3 adapted when 80 desired to be secured to the floor by a means of a plurality of bolts 4. The upper portion of the standard is provided with an enlarged head 2, upon which is positioned a table 5 of any suitable shape or size, and which is 85 adapted to be secured to the enlarged head by means of a plurality of bolts or other suitable fastening means 6. The main operating mechanisms are adapted to be supported in proper relation relative to each 90 other upon the table 5 to which they are firmly secured in such a manner as to retain them in proper position at all times.

Mounted upon the front edge of the table 5 is a block or casing 7 provided with an 100 outwardly extending base portion 8 which is firmly secured to the table by means of a plurality of bolts 9. The block or casing 7 may be constructed in any desired form which may be found to be applicable for 105 the particular use for which it is to be employed. In the present instance the block or casing is provided with a lateral open-

ing 10 formed in one side thereof and which in the present instance is illustrated as extending entirely through the block, although it will be understood that this opening may 5 terminate short of the opposite surface of the block if the use for which the structure is to be employed is such as to make such change advisable. The block is provided upon its upper surface with an angular 10 opening 11 and extending centrally from the angular opening 11 is a perforation 12 which extends through the upper portion of the casing or block and communicates with the lateral opening 10 previously described. A 15 perforation 13 is provided in the lower portion of the casing which is located in such a manner as to be in alignment with the perforation 12 formed in the upper side thereof and this perforation 13 extends 20 through the base portion of the casing and the table as shown in Figure V and is adapted to receive the upper end portion 14 of a spring pressed rod 15. The spring 25 pressed rod 15 is provided with an enlarged portion 16 which is adapted to fit within an opening 17 formed upon the under surface of the table in such a manner as to limit the upward movement of the rod 15. Pivotedly connected to the lower end portion 30 of the rod 15 is a connecting link 18 which is in turn pivotally connected as at 19 to a foot lever 20. The foot lever 20 is pivoted at one end to the standard 1 as at 21 and is normally maintained in raised position 35 by means of a resilient connection 22, one end of which is adapted to be secured to the table at 23.

An upright standard 25 preferably formed of a pair of channel members 26 is secured 40 to the upper surface of the table by means of a plurality of securing bolts 27, and extends upwardly therefrom forming the main support for the plunger and its operating mechanism. Firmly bolted to the front portion 45 of the upright standard 25 near the upper end thereof is a block 28 which has secured thereto a plurality of guide members 29 of suitable form and shape for the reception of the plunger 30. The guide 50 members 29 are so constructed as to permit the plunger 30 to glide freely therein, while they are located in such a position as to maintain the plunger at all times in alignment with the angular opening 11 formed upon the upper face of the block or casing 7. The plunger 30 is provided with a reduced end 31 formed upon the lower extremity thereof, which fits within the perforation 12 formed in the upper portion of 55 the block or casing 7.

Pivotedly mounted as at 32 upon the upper portion of the standard 25 is a support 33 to the upper end portion of which there is in turn pivotally mounted as at 34, a lever arm 35. The lever arm 35 is pivotally

connected to the upper end portion of the plunger as at 36 and the opposite end of the lever 35 is pivotally connected as at 37 to a piston rod 38. One end of the piston rod 38 has operatively secured thereto, a piston (not shown), which is slidably mounted within the cylinder 39. Firmly secured to the upper surface of the table in any suitable manner and extending rearwardly therefrom are a pair of bracket members 40, and the lower end portion of the cylinder 39 is pivotally connected to the brackets 40 as at 41 in such a manner as to enable the cylinder 39 to pivot thereon with sufficient freedom of movement to enable the same to 70 tilt slightly under certain conditions of operation of the mechanism. It will be noted that the support 33 is pivotally mounted at 75 32, and upon reference to Figures I and II of the drawings, it will be seen that both the cylinder and the support 33 are mounted so as to permit a slight tilting thereof in order to provide an arrangement of the parts which will permit the plunger 30 to move 80 freely between the guides 29 at all times. A resilient connection 42 connects the rear portion of the lever 35 with the base of the standard in such a manner as to enable the lever to be returned after it has been actuated by the piston rod 38.

The particular mechanism employed for operating the piston rod 38 and the lever connected therewith will now be described. While in the present embodiment of the invention, compressed air is employed for the purpose of actuating the plunger 30, it is to be understood that any desired motive force may be used therefor, such as an electric motor, or power may be taken from a shaft in a manner well understood in the art relating to power transmission. Secured to one side of one of the U-shaped channel members 26 in any suitable manner as by means of a bracket 44, is a pipe connection 45 provided at opposite ends thereof with valves 46 and 47, the valve 46 being adapted to control communication between the connection 45 and a compressed air supply pipe 48, while the valve 47 controls communication between the connection 45 and an exhaust pipe 49. A supply pipe 50 connects the pipe connection 45 with the base of the cylinder 39, being adapted to communicate with the cylinder beneath the lower most position of the piston head (not shown). The valves 46 and 47 are each adapted to be moved into closed position by means of a compression spring 52 while the valves are adapted to be opened by means under the control of the operator. The means employed for opening the valves comprises a lever arm 54 pivoted substantially centrally of its length to the bracket 44 as at 55 and provided at one end thereof with an offset handle 56. The opposite ends of the pivoted

lever 54 are adapted to constantly contact with the heads of the valves 46 and 47, the valves being constantly held in contact therewith by means of the coil springs 52. A 5 coil spring 57 secured to the end of the offset handle 56 and to a portion of one of the U-shaped channel members 26 serves to constantly retain the pivoted lever 54 in such a 10 position as to maintain the valve 47 open and the valve 46 closed, except when the pivoted lever is moved from this position by the operator for the purpose of actuating the mechanism.

In the embodiment of the invention illustrated herewith, a stop rod 58 is employed, which is secured in proper position by being adjustably attached to one of the U-shaped channel members 26 by means of nuts 59 at one end, while the opposite end of the stop 20 rod projects within the lateral opening formed in the block or casing 7 and serves as a stop for the elements adapted to be operated upon in such a manner as to insure the proper positioning of such elements with 25 respect to the perforations in the block or casing.

While this invention in its broader aspect relates to a mechanism adapted to be employed for the purpose of driving a pin within an opening formed in an element, or for driving a pin within registering openings formed in a pair of co-operating elements, in the specific embodiment of the invention illustrated herewith, the mechanism 30 is employed for the purpose of providing a ready means for easily forcing a pin within the registering openings in a piston head and the connecting rod co-operating therewith. It will be readily understood in 35 connection with the above statement that the block or casing 7 may be subjected to considerable modifications in order to properly adapt the same for use in connection with whatever element or elements it 40 may be desirable in practice to employ the mechanism. In the present instance, the lateral opening 10 formed in the block or casing is of such size and shape as to readily receive an engine piston A, the stop 58 45 extending to such a point as to contact with the head of the piston when the opening formed therein is in registry with the perforations 12 and 13 formed in the block or casing. A piston connecting rod B provided with an opening in one end thereof, 50 has the end portion containing the opening suitably positioned within the piston in such a manner that the opening formed therein will suitably register with the openings in the piston and the perforations 12 and 13 formed in the block or casing. When positioning these elements within the block or casing preparatory to the operations of forcing the pins within the 55 registering openings formed therein, the pedal

20 is depressed, thus withdrawing the upper end portion 14 of the rod 15 from the lateral opening 10 in the block or casing, and when the piston A and connecting rod B are properly placed in position in the manner described above, the pedal 20 is released whereby the rod 15 under the influence of the flexible connection 22 is drawn upwardly in such a manner that the upper end portion 14 thereof projects within the 70 openings formed in the piston head and connecting arm and serves to retain these parts in position so that the openings therein will be in proper alignment and be retained in such position while the pin C is 80 being driven within the registering openings. In this connection it is to be understood that the upper end portion 14 of the rod 15 is slightly smaller in diameter than the pin C, so as to enable it to readily enter the 85 openings in the piston head and connecting rod without being forced therein, while the portion 14 of the rod 15 is sufficiently large to retain the piston head and connecting rods in position with the openings therein 90 in alignment. The several parts being in the position described above, the pin C is inserted in the perforation 12 formed in the 95 upper face of the casing or block 10 in the position illustrated in Figure I, whereupon the operator grasps the offset handle 56 of the pivoted lever 54 and swings the same upon its pivot in such a manner as to force the valve 46 inwardly, thus placing the pipe 50 in communication with the compressed air pipe 48 and at the same time closing the valve 47 which communicates with the exhaust opening 49. Compressed air is thus 100 admitted to the cylinder 39 beneath the head of the piston (not shown), whereby the piston rod 38 is forced upwardly and the plunger 30 is reciprocated in a manner so that the reduced end portion 31 thereof, strikes the upper end of the pin C and 105 forces the same within the registering openings in the piston head and connecting arm, while at the same time the upper end 110 of the rod 15 is forced downwardly by the lower end of the pin C so that the parts occupy the position illustrated in Figure V. When the plunger has completed its downward movement the operative parts of the mechanism occupy the position illustrated 115 in Figure II, whereupon the operator releases the offset handle 56 of the lever 54 thus permitting the spring 57 to return the lever to its normal position and open the valve 47 between the outlet 49 and the cylinder. The spring 52 which actuates the valve 46 immediately closes the communication between the connection 45 and the supply pipe 48, and the compressed air in the cylinder 39 is permitted to pass freely 120 to the atmosphere through the exhaust pipe 49. The flexible connection 42 immediately 125

returns the lever 35 and plunger 30 to their normal position, as illustrated in Figure I, when the compressed air in the cylinder 39 has escaped.

5 It will be clear from the above description, that the mechanism as described here-with provides a ready and efficient means for readily and easily performing the operation of driving a pin within the register-
10 ing openings in a piston head and the connecting rod associated therewith, while at the same time insuring that the parts be retained in such a position as to prevent distortion or injury thereto. By means of
15 the mechanism described, this operation is capable of being performed by ordinary unskilled labor and with considerably greater rapidity than is possible if it is necessary to employ the means in common use.

20 While I have shown and described in considerable detail, a specific embodiment of my invention, it is to be understood that this showing and description is illustrative only and for the purpose of rendering my invention more clear and that I do not regard the invention as limited to the details of construction illustrated or described, nor any of them, except in so far as I have included such limitations within the terms of
25 30 the following claims, in which it is my intention to claim all novelty inherent in my invention broadly as well as specifically.

What I claim as new and desire to secure by Letters Patent is:

35 1. In a device of the class described, a casing provided with an opening therein, in which opening a work element is adapted to fit, said element having an opening through which a pin is to be driven, and means for
40 forcing the pin into the opening in the element while the same is positioned within the casing.

2. In a device of the class described in combination, an integral casing provided with top and side openings therein, the opening in the side of the casing being adapted to receive and position a work element having an opening therethrough, the opening in the top of said casing being adapted to hold a pin to be driven through the opening in the work element, and means for forcing the pin into the work element.

3. In a device of the class described, in combination, a block provided with a perforation, means for retaining a work element having an opening in such a position that the opening in the element will be in registry with the perforation in the block, and means for forcing a pin within the opening in the element.

4. In a device of the class described in combination, a block, means for maintaining an opening in a work element in a fixed position relative to the block, means for positioning a pin in alignment with the opening

in the work element, and means for forcing the pin within the opening in the element.

5. In a device of the class described, in combination, means for maintaining a pair of perforated work elements in such a position that the perforations of the elements will be in alignment and means for forcing another work element in the shape of a pin, into the registering perforations in the pair of work elements.

6. In a device of the class described, a perforated block, a spring actuated rod a portion of which is adapted to extend within the perforation in the block, and a plunger provided with a portion adapted to be forced within the perforation of the block in such a manner as to be in substantial alignment with the spring pressed rod.

7. In a device of the class described, a perforated block, a spring pressed rod a portion of which is adapted to extend within the perforation in the block, a plunger provided with a reduced portion in substantial alignment with the spring pressed rod, and means for forcing the reduced portion of the plunger within the perforation in the block.

8. In a device of the class described, a perforated block, a spring pressed rod a portion of which is adapted to extend within the perforation in the block, a plunger located upon the opposite side of the perforated block from the spring pressed rod, and means for actuating said plunger.

9. In a device of the class described, a perforated block, a spring pressed rod a portion of which is adapted to extend within the perforation in the block, a plunger located upon the opposite side of the perforated block from the spring pressed rod, actuating means for forcing the plunger toward the block, and means for withdrawing the plunger when the actuating means is suspended from operation.

10. In a device of the class described, a perforated block, a plunger positioned in substantial alignment with the perforation in the block, actuating means for forcing the plunger towards the block comprising a pivotally mounted cylinder, and means for returning the plunger to its normal position upon release of the actuating means.

11. In a device of the class described, a perforated block provided with a passage adapted to hold a perforated element to be operated on by the device, means for aligning the perforations in the block and the work element and means for limiting the movement of the work element in the passage in the block and cooperating with the first mentioned means to bring the perforations into registry.

12. In a device of the class described, a perforated block, a spring-pressed rod, a portion of which is adapted to extend with-

in the perforation in the block, means on the rod to limit the movement of the rod, a plunger located upon the opposite side of the perforated block from the spring-pressed rod, and means for forcing the plunger towards the block.

13. In a device of the class described, a perforated block provided with a passage for the reception of a perforated work element to be operated on, a spring-pressed rod, a portion of which is adapted to extend within the perforations of the block and work element, a plunger located upon the opposite side of the perforated block from the spring-pressed rod, and means for forcing the plunger towards the block.

14. In a device of the class described, a perforated block provided with a passage for the reception of a perforated work element through which perforation in the element a pin is to be driven, a spring-pressed rod, a portion of which is adapted to extend within the perforations of the block and the work element to align the same, a plunger located upon the opposite side of the perforated block from the spring-pressed rod and adapted when operated to drive the pin through the perforation in the work element, and pivotally mounted actuating means for operating the plunger.

15. In a device of the class described, a perforated block, a passage in the block at right angles to the perforation, the said passage being adapted to hold a perforated work element, a stop for positioning the

work element, a spring-pressed rod for aligning the perforations in the work element and the block, a plunger adapted to drive a pin through the aligned perforations, and pivotally mounted means for operating said plunger.

16. In a device of the class described, a block provided with a cylindrical passage adapted to hold an element to be operated on, the said element being in the shape of a cylindrical piston, means to limit the longitudinal movement of the piston in the passage, and means for circumferentially positioning the piston in the passage.

17. In a device of the class described, a perforated block, a spring-pressed rod adapted to be reciprocated in the perforation, a plunger adapted to be forced within the perforation upon the opposite side of the perforated block from the spring-pressed rod, and means on the plunger to limit the movement of the plunger in the perforation.

18. In a device of the class described, a perforated block, having a socket for holding a pair of perforated elements to be operated on by the device, and a common means for aligning the perforations in the elements and also for positioning the one of the elements in the block so that the perforation in said elements will register with the perforation in the block.

In testimony whereof, I affix my signature.

GRANT W. ROLLINS.
